UNITED STATES PATENT OFFICE.

WILSON J. GILLAM, OF SAYVILLE, NEW YORK, ASSIGNOR TO SAYVILLE FURNITURE COMPANY, INC., OF SAYVILLE, NEW YORK, A CORPORATION OF NEW YORK.

DESIGN FOR A CHAIR.

Application filed May 23, 1922. Serial No. 2,373. Term of patent 14 years.

To all whom it may concern:

Be it known that I, WILSON J. GILLAM, a citizen of the United States, residing at Sayville, in the county of Suffolk, State of New York, have invented a new, original, and ornamental Design for Chairs, of which the following is a specification, reference being had to the accompanying drawing, forming part thereof.

The figure is a perspective view of a chair, showing my new design.

I claim:—

The ornamental design for a chair, as shown.

WILSON J. GILLAM.
